(57) **CLAIM**

The ornamental design for a screw, as shown and described.

DESCRIPTION

FIG. 1 is a perspective view of the design of a screw; FIG. 2 is a back plan view of the screw shown in FIG. 1; FIG. 3 is a front plan view of the screw shown in FIG. 1; FIG. 4 is a top side view of the screw shown in FIG. 1; FIG. 5 is a back side view of the screw shown in FIG. 1; FIG. 6 is a left side view of the screw shown in FIG. 1; and, FIG. 7 is a right side view of the screw shown in FIG. 1. Any features shown in broken lines depict environmental subject matter only and form no part of the claimed design.

1 Claim, 3 Drawing Sheets
